(57) **CLAIM**

The ornamental design for a handle for display signs, as shown and described.

DESCRIPTION

FIG. 1 is a perspective view from above and one side of a handle for display signs according to my design;

FIG. 2 is a side elevational view taken from the left side of FIG. 1, the opposite side being a mirror image;

FIG. 3 is a top plan view of the handle for display signs;

FIG. 4 is a front end elevational view of the handle for display signs;

FIG. 5 is a bottom plan view of the handle for display signs; and,

FIG. 6 is a perspective view similar to FIG. 1 showing a display sign in ghost outline to the handle for display signs. The broken line showing the display sign in FIG. 6 is for illustrative purposes only and forms no part of the claimed design.
